His attys.

UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

CHAIN-GUIDE FOR PULL-SOCKETS.

1,233,339.

Specification of Letters Patent. Patented July 17, 1917.

Application filed November 21, 1916. Serial No. 132,605.

To all whom it may concern:

Be it known that I, DAVID D. GORDON, a citizen of the United States, and a resident of Chicago, in the county of Cook and State of Illinois, have invented a certain new and useful Chain-Guide for Pull-Sockets; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to electrical sockets of the pull chain type and particularly to guides for the pull chains or cords thereof.

An object of my invention is the provision of improved means for attaching chain guides to pull sockets in a simple and efficient manner whereby to enhance the practicability and commercial value of such sockets and to enable the guides to be quickly applied to or removed from the 25 sockets.

A further object of my invention is the provision in an electrical socket having separable top and bottom members forming an insulating switch carrying body, of an improved chain guide which is detachably secured to said body members and adapted to assist in retaining such members in assembled relation.

The invention is fully described in the 30 following specification, and while, in its broader aspect, it is capable of embodiment in numerous forms, a preferred embodiment thereof is illustrated in the accompanying drawings, in which—

40 Figure 1 is a side elevation of a socket embodying the invention, with a portion of the shell broken away. Fig. 2 is a top plan view thereof with the shell cap removed. Fig. 3 is a side elevation of the socket with the shell and chain guide removed, and Fig. 4 is a view of a chain guide embodying the 45 invention.

Referring to the drawings, 1 and 2 designate the base and cap members, respectively, 50 of the shell of an electrical socket, which members may be separately secured together in any suitable or convenient manner, as is well understood in the art. The switch carrying body of the socket comprises the base and cap members 3 and 4, respectively, which

are mounted one on top of the other and inclose the switch mechanism. These body members may be separably secured together by spring fingers or in any other suitable manner (not shown) as well understood in 60 the art, or they may be placed loosely one on top of the other and held in assembled relation by the inclosing shell, in conjunction with the means hereinafter described. An insulating lining 5 is disposed between 65 the shell and switch body as is customary in sockets of this character.

The pull chain 6 for operating the switch mechanism extends out from the interior of the switch body through an opening 7, provided in one side thereof, and thence through a chain guide 8, which extends from the outer end of the opening 7 out through a registering opening 9 provided in the shell base 1 and insulating lining 5, said opening 70 extending to the upper ends of said parts and being closed above the guide by the shell cap 2 when mounted on the base 1, as is customary in sockets of this character.

The chain guide 8, in the present instance, 75 is of bell form and is provided at its inner end with a base plate 10, which is adapted to fit against the side of the switch body. The plate 10 is elongated lengthwise of the switch body to adapt it to extend in both 80 directions beyond the point of division of the members of said body, and has one end, the upper in the present instance, provided with inwardly turned L-shaped fingers 11

which project into a recess or pocket 12 provided in a side of the body member 4 and have their angled ends fitting into registering sockets 13 provided in the base wall of 85 said recess. It is thus evident that the upper end of the plate 10 is adapted to have 90 hooked engagement with the body member 4 to prevent a transverse withdrawing of such fingers from engagement with the body member except when the fingers are moved upward to disengage their hooked or angled ends from within the holding sockets 13. While it is preferable to provide the 95 fingers 11 with the angled end portions for hooked engagement with the socket body, these fingers may be made straight if desired without departing from the spirit of the invention.

The opposite end of the plate 10 is provided with an inturned finger 14, which is adapted to project within a registering re- 100

105

110

cess 15 provided in the body member 3 in outwardly spaced relation to its inner end. The space between the bottom walls of the recesses 12 and 15 is substantially equal to 5 the space between the fingers 11 and 14 so that such fingers when projected into the respective recesses coat with the bottoms thereof in opposed relation and serve to retain the members of the socket body in assembled relation. It is apparent that in engaging the chain-guide plate 10 with the socket body, if the fingers 11 are of angled form, it is necessary to first place the fingers 11 in hooked engagement with the recess 12 10 and recesses 13 thereof and then to swing the opposite end of the plate inward toward the socket body to project the finger 14 into the recess 15. The plate 10 is then retained to the socket body in this position by the 15 shell base 1 and lining 5, when slipped over said body, or by the shell alone if the plate 10 is too thick or projects too great a distance from the side of the socket body to permit the interposition of the lining between the plate and shell, in which case the lining may be cut away to receive said plate.

It is evident that I have provided a simple and efficient means for attaching a chain guide to a socket and that it is also adapted 20 to serve as a means for retaining the members of the socket body in assembled relation.

I wish it understood that my invention is not limited to any specific construction, arrangement or form of the parts as it is capable of numerous modifications without departing from the spirit of the claims.

Having thus described my invention, what I claim as new, and desire to secure by 25 Letters Patent, is,—

1. In an electric socket, an insulating body having longitudinally separable members forming a switch housing, and a chain guide projecting outward from a side of 30 said body and having fingers projecting

transversely from its inner end in opposed relation, said fingers bearing inward against a side of said body and angled at their ends to enter registering portions of respective body members to prevent a longitudinal separation thereof. 50

2. In an electrical socket, an insulating body having separable base and cap members with each member provided in a side thereof with a recess which is outwardly spaced from its inner end, and a chain guide having a plate at its inner end for resting against the outer side portion of said body and having fingers at its opposite end portions for insertion into the recesses of said 60 members whereby the plate and fingers cooperate with the adjacent walls of the recesses to retain the body members in assembled relation.

3. In an electrical socket, an insulating 65 body provided in a side thereof with longitudinally spaced recesses, and a chain guide having a plate at its inner end for resting against the outer side portion of said body and having fingers at its ends for projecting 70 into respective recesses with a finger at one end angled and in hooked engagement with a wall of its recess.

4. In an electrical socket, an insulating body having separable base and cap portions each provided with a recess in a side thereof in outwardly spaced relation to its inner end, and a chain guide having a plate at its inner end for resting against the outer side portion of said body in spanning relation to the dividing line between its members and having hooked means at one end for projecting into and interengaging with a wall of one of said recesses and a finger at its other end for projecting into the other 85 of said recesses.

In testimony whereof, I have hereunto signed my name to this specification.

DAVID D. GORDON.
